UNITED STATES PATENT OFFICE.

JOHN E. MOORE, JOHN BLACK, JR., JOHN C. CROSBY, AND JOHN BLACK, OF WALTERBORO, SOUTH CAROLINA.

TORPEDO-SHIELD.

1,309,690.

Specification of Letters Patent. Patented July 15, 1919.

Application filed June 6, 1917. Serial No. 173,179.

To all whom it may concern:

Be it known that we, JOHN E. MOORE, JOHN BLACK, Jr., JOHN C. CROSBY, and JOHN BLACK, citizens of the United States 5 of America, and residents of Walterboro, South Carolina, have invented a new and useful Improvement in Torpedo-Shields, which invention is fully set forth in the following specification.

10 This invention relates to torpedo shields, and has for its object to provide a device of the above character which is designed to minimize the chances of explosion when the torpedo hits the shield and to reduce the 15 chances of serious injury to the vessel either by impact with the torpedo or by an explosion if the latter should occur.

The invention resides in providing an open-work shield, such as iron lattice-work 20 or other surface provided with openings, with torpedo-deflecting projections surrounding openings in the shield and interposing between the hull of the vessel and the shield a plurality of yielding resistances for 25 taking up impact. The open-work shield may assume various forms, but preferably is made by riveting strips of steel together to form a lattice-work, the openings or meshes of which are large enough to receive

30 the nose or firing end of a torpedo, and too small to permit the passage of the body of the torpedo. The deflecting projections are preferably struck up from sheet metal, and are given a cone or pyramidal shape suitable 35 for guiding the nose of the torpedo when it strikes the slanting sides of the projections into one of the holes or meshes prepared to receive it. The yielding resistances are preferably in the form of springs placed

40 opposite openings in the shield and abut at their inner ends against the hull. The shield structure may be supported in any suitable manner which permits its surface to yield, as by means of spars or iron braces made 45 fast to the hull and slidably connected with the shield. The shield preferably is designed to extend in a wide band from stem to stem, but may be made to surround the entire hull.

50 When a torpedo hits the shield as thus constructed, the nose or firing end glides down the side of one of the cone projections, and is guided by its companion projections into one of the openings or meshes in the 55 shield, without meeting resistance sufficient

to cause the detonating plunger in the head to function and effect an explosion. Should an explosion occur, however, the center of explosion is removed from the surface of the hull and the shock is lessened by the 60 cushioning action of the springs. The impact of the torpedo when it does not explode is safely cushioned by the springs.

In order that the invention may be more readily understood, reference is had to the 65 accompanying drawings, which illustrate, by way of example, one mechanical expression of the inventive idea, and are designed as illustrations to assist the description of the invention, and not as defining the limits 70 thereof.

In said drawings:—

Figure 1 is a plan view of the torpedo shield made in accordance with our invention;

Fig. 2 is a vertical sectional view of a portion of a vessel's hull showing the shield in position;

Fig. 3 is an elevational detail view showing the torpedo-deflecting projections 80 mounted on the open-work shield;

Fig. 4 is a vertical sectional detail showing the manner of slidably supporting the shield;

Figs. 5, 6 and 7 are other detail views.

Referring to the drawings, 1 indicates a sectional portion of a hull of a vessel on which is supported at some distance therefrom an open-work structure 2 which, as indicated in Fig. 1, may surround the hull of 90 the vessel and extend below the water-line to any suitable distance for the protection of the hull. The open-work structure 2 is supported by aid of brackets 3 fastened at their inner ends to the vessel at suitable intervals, their outer ends terminating in cone-shaped projections 5 and adapted to receive the threaded ends of shield-supporting rods 4 on which slide frusto-conical heads 6 riveted or otherwise secured to the 100 open-work 2 and adapted to fit under the ends of the brackets 3. See particularly Fig. 4. Interposed between the open-work 2 and the hull of the vessel are a plurality of coiled springs 7, the opposite ends of which 105 are held in place by clamping means, such as by threaded claw-shaped members 8 each adapted to take through the sheathing or shield and clasp the end spiral of the spring against the adjacent supporting surface by 110

aid of a nut. The open-work structure 2 consists of a series of parallel sheet-metal strips 9 spaced from each other and across which are bolted, riveted or otherwise secured another series of similar parallel strips 10 also spaced at suitable distances to form therewith a checker-work. Over alternate meshes of this structure, flanged cone-shaped deflecting projections 11 are bolted. 5 Between each pair of oppositely inclined faces occurs an opening 12 in the mesh, and an opening 13 also occurs in the mesh at the diagonal intersection of lines through the axes of the projections. Opposite the openings 13, the spiral springs 7 are positioned. The openings are of a size adapted to receive the firing end of a torpedo and to exclude the passage of the body portion. 10

The operation of the device as thus far described will be readily understood from the above description and, briefly stated, is as follows: Assume that the shield has been assembled and placed in position as indicated in the drawings. When a torpedo hits the shield, the chances are that the firing end of the torpedo hits one of the inclined surfaces of one of the projections 11 directing its course into one of the openings 12 or 13 arranged for its reception. Owing to the 15 construction and arrangement of the projections, a normal blow on the percussion piston in the head of the torpedo is avoided and a glancing blow is given this member, thereby reducing the chances of its properly functioning to explode the charge. After the 20 nose of the torpedo enters an opening in the shield, the shoulders back of the head meet the faces of the spring-cushioned projections 11 which slide back on their sup-

porting rods 4, thereby compressing the 40 springs 7 which take up the shock of the collision. Should, however, the torpedo explode, due to the fact that its nose or firing end struck a point of a projection or for other reason, the danger to the vessel due 45 to such an explosion is materially reduced, because of the removal of the explosion to a distance from the hull and also to the fact that part of the explosive effect is taken up by the resilient backing of the shield. 50

What is claimed is:—

1. A torpedo shield for vessels, comprising a spring-pressed open-work structure provided with torpedo-deflecting projections distributed over the face of said structure 55 and alternating with openings therein, each projection having surfaces inclined to said face for directing the firing end of the torpedo into one of said openings, and supports for the structure fast to the hull, said 60 structure having slidable connection with said supports.

2. A torpedo shield for vessels, comprising a spring-pressed open-work structure, supports for the same fast to the hull, said 65 structure having slidable connection with said supports, and torpedo-deflecting projections distributed over the face of said structure and alternating with openings therein, each projection having surfaces inclined to said face for directing a torpedo into one of said openings. 70

In testimony whereof we have signed this specification.

JOHN E. MOORE.
